R. S. C. Dougherty.

ATTORNEY

UNITED STATES PATENT OFFICE.

NEIL E. SALSICH, OF BETHLEHEM, PENNSYLVANIA.

GAUGE ROD.

Application filed March 6, 1926. Serial No. 92,815.

My invention relates to gauge rods of the type having relatively adjustable jaws or clips to engage over the flanges of trackway rails.

5 A gauge rod of the type having a fixed jaw or clip at one end and a movable jaw or clip at the other end, the fixed jaw engaging over the outside flange of one rail and the movable jaw engaging over the outside flange of the other rail of a trackway and the movable jaw being forced inwardly by a nut carried by the rod, has been used; however, this type of gauge rod construction is faulty for the reason that heretofore in- 10 adequate bearing area of the movable jaw member beneath the bottom of a rail was afforded in order to effectively resist any tendency of the jaw to bend the rod when gripped with a rail flange. Accordingly, therefore, it is the object of my invention to provide a gauge rod construction of this type wherein the movable jaw member shall have a portion for engagement beneath the bottom of a rail for a sufficient distance 15 widthwise in order to effectively resist any tilting tendency of the member, such tilting tendency having heretofore been manifested with movable jaws and resulted in bending and fracturing of rods.

20 Another object of my invention is the provision of a movable jaw member having an opening for receiving the tensioning rod positioned so that the latter is disposed substantially parallel with the base of the track rails when the jaws are engaged to the latter, and the clamping action of said rod is applied in close proximity to said base so as to effectively resist the tendency of the rod to bend or flex.

25 The novel features will be more fully understood from the following description and claims taken with the drawings, in which:

30 Fig. 1 is a perspective view of a gauge rod showing my improved jaw member applied thereto;

35 Fig. 2 is a side elevation of the movable jaw;

40 Figs. 3 and 4 are detail views of a modified form of movable jaw member; and,

45 Fig. 5 is a detail view showing a further modified form of movable jaw member.

50 Referring now to the drawings more in detail for a better understanding of my invention, in Figs. 1 and 2, I show a tensioning rod 10 having a fixed jaw 11 at one end for engagement over the outside flange of one

55 rail of a track. The other end of the rod 10 is threaded at 12. A movable jaw 13 fits over the threaded end 12, and nut means 14 engages the threaded portion 12 in order to force the movable jaw 13 inwardly to engage the latter over the outside flange of the other rail of a trackway.

60 The movable jaw 13 is comprised of a U-shaped sleeve portion 15 adapted to partially surround the rod 10 and having rail bearing surfaces 16 extending laterally from opposite sides thereof adapted to engage the bottom of a rail. The outer end of the jaw 13 is provided with an overhanging member 17 adapted to engage the upper surface of a rail flange and is connected to the sleeve portion 15 by the wall 18. The overhanging member 17 is provided with a clearance space 19, adjacent the wall 18, whereby it is assured that said member firmly engages the upper surface of a rail flange. This feature permits the firm engagement with the rail flanges of different thicknesses. An opening 20 is provided in the wall 18 to receive the rod 10. This opening 20 is aligned with the inner cylindrical surface of the sleeve portion 15 and it is positioned so that when the jaws engage the track rails the rod 10 is in close proximity to the base of the rails 65 and substantially parallel to the latter. This provides a feature whereby it is assured that pull on the rod 10 is more or less in longitudinal direction and effectively resists the tendency of the rod to flex laterally and 70 bend when the jaws are engaged to the track rails.

75 The movable jaw member 13 is preferably made of malleable cast iron; and, as illustrated, it is provided with ribs for strengthening purposes. As shown in Figs. 1 and 2 the overhanging portion 17 consists of a plurality of fingers 21 in order to facilitate a more uniform gripping relation with respect to an outside rail flange, and the fingers are 80 strengthened by connecting webs 21'.

85 The movable jaw 13 extends inwardly beneath the bottom of a rail a sufficient distance, preferably not less than one-half the width of a rail bottom, to effectively resist any tendency of the movable member setting up a tilting action tending to bend the rod 90 when the nut means 14 is screwed home.

95 In Figs. 3 and 4, I show a modified rail jaw member of a design which may be readily forged, the jaw having a hook portion 22 and leg portions 23, the hook portion 100

22 and the leg portions 23 being integral with the body portion 24 and the latter having an opening 25 through which the threaded end 12' of a gauge rod passes. The portions 23 are bent substantially at right angles to the body portion 24 and are adapted to extend beneath and preferably beyond the medial line of the rail to engage the bottom of a rail in order to effectively 10 resist any tendency to tilting of the hook member or jaw which, in turn, would tend to bend or flex the rod. The hook portion 22 is bent up at 26 to provide a clearance space 18' for the same purpose as the space 19 15 already described.

It will be noted in the designs shown in Figs. 2 and 3 that the opening 25 is located with reference to the upper surface of the leg portions 23 so that the rod 10 is in close 20 proximity to the base of the rail and substantially parallel thereto when the jaws engage the rail flanges.

In Fig. 5, I show a drop forged type of jaw member similar to that shown in Figs. 25 3 and 4 but in which the body portion 24' is provided with a sleeve or thimble 27 which is pressed in the opening 25, and fits about the threaded end 12' of a gauge rod.

The portion of the sleeve 27 which extends laterally from the face of the body portion is preferably cut away, as at 28, to enable the opening to be so located that the rod is in close proximity to the rail base. 30

From the foregoing, it will be apparent 35 that I have devised a gauge rod having a movable jaw provided with a bearing portion to engage beneath a track rail and which bearing portion is of sufficient extent to resist any tilting action of the jaw 40 when engaged with a rail flange, whereby, bending or flexing of gauge rods is avoided and breakage of the latter due thereto is also avoided.

Furthermore, my device is so constructed 45 that the tension rod is disposed in close proximity to the rail base and substantially parallel thereto, so that the pull on the rod is more or less in a true longitudinal direction and effectively resists the tendency to 50 flex or bend when the jaws engage the track rail flanges.

While I have shown my invention in a plurality of forms it will be obvious to those skilled in the art that it is not so limited, 55 but is susceptible of various other changes and modifications without departing from the spirit thereof, and I desire, therefore, that only such limitations shall be placed thereupon as are imposed by the prior art 60 or as are specifically set forth in the appended claims.

Having thus described the invention what I claim as new and desire to secure by Letters Patent is:

65 1. In a gauge rod construction for engage-

ment with the outside flanges of the rails of a track, the combination of a rod having a jaw fixed to one end thereof and having its other end threaded, a jaw movable longitudinally of the rod and having a bearing portion adapted to engage a rail bottom for substantially the width of the latter and having an overhanging member provided with a bearing surface adapted to engage the top surface of a rail flange, said member providing a clearance space between said bearing surface and the portion thereof joined to the body of the jaw, whereby said bearing surface may be caused to engage top surfaces of rail flanges of varying thicknesses, and nut means carried by the threaded end of the rod to cause the jaws to approach and firmly grip the outside flanges of the rails of a track.

2. In a gauge rod device, the combination of a rod member having a fixed jaw at one end and having its other end threaded, a movable jaw mounted on said rod and in opposed relation with respect to the fixed jaw, said movable jaw having a rail engaging portion adapted to extend beneath and engage a rail bottom for a distance not less than one-half the width of a rail base and having a U-shaped sleeve portion adapted to partially surround said rod and also having an outer overhanging portion adapted to engage over an outside flange of a trackway rail, said overhanging portion provided with a bearing surface adapted to engage the top surface of a rail flange and providing a clearance space between said bearing surface and the portion thereof joined to the body of the jaw, whereby said bearing surface may be caused to engage top surfaces of rail flanges of varying thicknesses, and nut means engaging the threaded end of the rod to cause the movable jaw to move inwardly to engage the flange of a track rail.

3. In a gauge rod device, the combination of a rod member having a fixed jaw at one end and having its other end threaded, a movable jaw mounted on said rod and in opposed relation with respect to the fixed jaw, said movable jaw having a rail engaging portion adapted to extend beneath and engage a rail bottom for a distance not less than one-half the width of a rail base and having a U-shaped sleeve portion adapted to partially surround said rod and also having an outer overhanging portion adapted to engage over an outside flange of a trackway rail, said overhanging portion provided with a bearing surface adapted to engage the top surface of a rail flange and providing a clearance space between said bearing surface and the portion thereof joined to the body of the jaw, whereby said bearing surface may be caused to engage top surfaces of rail flanges of varying thicknesses,

said movable jaw being provided with an opening receptive of said rod, said opening being positioned with respect to said rail engaging portion so that when said jaws engage the flanges of the track rails the rod is disposed substantially parallel to the base surfaces of said rails and in close proximity thereto, and nut means engaging the threaded end of the rod to cause the movable jaw 10 to move inwardly to engage the flange of a track rail.

4. In a gauge rod device, the combination of a rod member having a fixed jaw at one end and having its other end threaded, a movable jaw mounted on said rod and in opposite relation with respect to the fixed jaw, said movable jaw being of substantially uniform thickness throughout and having a vertically disposed body portion, a pair of spaced leg portions extending laterally from said body portion adapted to extend beneath and engage a rail bottom for a distance not less than one half the width of a rail base, an overhanging portion extending upwardly and inwardly from said body portion adapted to engage over an outside flange of a trackway rail, said overhanging portion provided with a bearing surface adapted to engage the top surface of a rail flange and being depressed to provide a clearance space between said bearing surface and the body portion, whereby said bearing surface may be caused to engage top surfaces of rail flanges of varying thicknesses, and nut means engaging the threaded end of the rod to cause the movable jaw to move inwardly to engage the flange of a track rail.

5. In a gauge rod device, the combination of a rod member having a fixed jaw at one end and having its other end threaded, a movable jaw mounted on said rod and in opposite relation with respect to the fixed

jaw, said movable jaw being of substantially uniform thickness throughout and having a vertically disposed body portion, a pair of spaced leg portions extending laterally from said body portion adapted to extend beneath and engage a rail bottom, an overhanging portion extending upwardly and inwardly from said body portion adapted to engage over an outside flange of a trackway rail, said overhanging portion provided with a bearing surface adapted to engage the top surface of a rail flange and being depressed to provide a clearance space between said bearing surface and the body portion, whereby said bearing surface may be caused to engage top surfaces of rail flanges of varying thicknesses, and nut means engaging the threaded end of the rod to cause the movable jaw to move inwardly to engage the flange of a track rail.

6. In a gauge rod device, the combination of a rod member having a fixed jaw at one end and having its other end threaded, a movable jaw mounted on said rod and in opposite relation with respect to the fixed jaw, said movable jaw being of substantially uniform thickness throughout and having a vertically disposed body portion, a pair of spaced leg portions extending laterally from said body portion adapted to extend beneath and engage a rail bottom, an overhanging portion extending upwardly and inwardly from said body portion adapted to engage over an outside flange of a trackway rail, said overhanging portion provided with a bearing surface adapted to engage the top surface of a rail flange, and nut means engaging the threaded end of the rod to cause the movable jaw to move inwardly to engage the flange of a track rail.

In testimony whereof I hereunto affix my signature this 5th day of March, 1926.

NEIL E. SALSICH.
